PICKER STICK CHECK STRAP FOR LOOMS AND METHOD OF MAKING THE SAME

Albert A. Robert, Tilton, N. H., assignor to Arthur S. Brown Mfg. Co., Tilton, N. H., a corporation of New Hampshire

Application January 18, 1954, Serial No. 404,571

10

2 Claims. (Cl. 139—161)

This invention relates to a picker stick check strap for looms of that known type which is in the form of an endless elongated loop through which the picker stick extends and the elongated sides of which are frictionally supported in a suitable supporting bracket attached to the lay of the loom.

One object of the present invention is to provide a picker stick check strap of this type which has increased strength and superior wearing qualities and which is also slightly resilient in the direction of its length so that at each impact of the picker stick against either end of the loop the check strap will yield slightly thereby cushioning such impact and reducing the strain on the check strap caused by such impact.

My improved check strap is made from a tubular woven fabric which presents heavy warp threads of cotton, nylon or other suitable synthetic fibre extending lengthwise of said fabric and a filling or weft thread of nylon, or other similar synthetic material, which extends circumferentially of the fabric.

In the drawings, wherein I have illustrated various steps involved in the making of the check strap,

Fig. 1 indicates a length of tubular woven fabric having the heavy warp threads of cotton, nylon or other synthetic fibre and the nylon filling or weft thread;

Fig. 2 illustrates the operation of impregnating the fabric with a liquid rubber latex compound;

Fig. 3 shows a section of the tubular fabric from which a single check strap is to be made;

Fig. 4 is a sectional perspective view showing the first step of folding the section of tubular fabric;

Fig. 5 is a similar view illustrating the second step of folding the fabric to produce a four-ply structure;

Fig. 6 is a sectional perspective view showing the four-ply fabric provided with lines of stitching extending circumferentially thereof;

Fig. 7 illustrates the step of dipping the article shown in Fig. 6 in a bath of liquid latex compound;

Fig. 8 is a perspective view of the completed check strap;

Fig. 9 illustrates the manner in which the check strap is used in a loom.

In the drawings 1 indicates a length of woven tubular fabric from which my improved check strap may be made, said fabric having the longitudinally extending heavy warp threads 2 of cotton, nylon, or other synthetic fibre, and the continuous weft or filling thread 3 which extends circumferentially of the fabric in the form of a multiplicity of integrally connected loop turns which are interwoven with the warp threads 2. The weft thread 3 is preferably made of nylon, or some other synthetic fibre, which is extremely strong, but more or less elastic, and the weft and warp threads may be woven in the manner of a plain weave or in the manner of a rib weave.

After a suitable length of tubular fabric 1 has been woven it is impregnated with a liquid rubber latex compound, preferably of the type commercially known as K5

2

Red, or a solvent-dispersed rubber compound such as is known to the trade as K7 Black. The impregnation of the length of tubular fabric is illustrated in Fig. 2 wherein 4 indicates a tub or vat containing the liquid rubber compound, and into which a length of the tubular fabric 1 is immersed.

After the length of fabric has been properly impregnated with the liquid rubber compound it is either hung up to drain or may be run through squeeze rollers to squeeze out excess impregnating liquid. When the impregnated length of fabric 1 has been dried sufficiently so that it can be handled then it is cut transversely along the lines 5 in Fig. 1, thereby dividing the length of tubular fabric into sections indicated at 5 in Fig. 1, each section being of a width to produce one check strap. One of these sections is illustrated in Fig. 3. The material with which the tubular fabric is impregnated serves to prevent any raveling of the weft thread 3 at either edge of the section 5.

The edges 6 and 7 of each section 5 are then folded inwardly, as shown in Fig. 4, so that the marginal portions of said edges come close together along a median line.

The section folded, as shown in Fig. 4, is then folded inwardly again along the median line to produce the four-ply article shown in Fig. 5, the cut edges 8 and the folded portions 6, 7, being enclosed between the portions 9 and 10.

This makes an article in the form of an endless loop having at one edge the two folded edges 11 and at the other edge the single folded edge 12, the sides of the loop having a uniform thickness throughout.

The four plies of the article are then stitched together by a plurality of lines of stitching 13 which run around the article parallel to the weft threads 3 as seen in Fig. 6. If desired the folded article shown in Fig. 5 may be run between compressing rolls to press the plies firmly together before the lines of stitching 13 are inserted.

The stitched article is then again immersed in a liquid rubber latex compound, as shown in Fig. 7, thereby completing the saturation thereof and providing it with a surface coating.

The article is then removed from the bath 14, shown in Fig. 7, and after it is properly dried and cured it is ready for use, as seen in Fig. 8. This check strap, as above described, is intended to be supported in position on the lay of the loom by means of suitable supporting brackets which are attached to the lay and each of which has the three depending fingers 15, 16, and 17, each side of the elongated check strap being threaded through the fingers of its supporting bracket, as shown in Fig. 9.

Because of the relative location of the fingers 15, 16, and 17, each side of the loop will be bent around the central finger so that the loop is frictionally retained in place and is capable of a slight movement in the direction of its length at each impact of the picker stick which is indicated at 20.

It will be understood that the check strap is supported in a position in which the picker stick oscillates back and forth between the sides of the strap, as indicated in dotted lines in Fig. 9. At the end of each forward movement of the picker stick it will engage and be arrested by the right hand end 21 of the check strap and at each return movement of the picker stick it will engage and be arrested by the end 22 of said strap.

The impact of the picker stick against the ends of the check strap is taken by the weft thread 3 which, as stated above, is preferably a nylon thread which is exceedingly strong, but is somewhat elastic. The strength of the nylon thread which absorbs the impact of the picker stick at each end of its throw provides a check strap which has superior strength and the elastic characteristic of the

nylon permits the check strap to give slightly at each impact, thereby providing a cushioning effect which adds to the length of life of the strap.

While I have shown a four-ply check strap, yet it will be obvious that a check strap having six or eight plies might be made from a section of a tubing by properly folding said section.

Another advantage inherent in a picker check strap embodying the invention is that although when the strap is first installed the picker stick strikes the upper edge of the strap at each end of its throw, yet because of the elasticity of the nylon thread the upper edge portion of the strap will gradually increase slightly in diameter so that eventually the picker stick at each end of its throw will strike flatly against the end of the strap and this is a feature which reduces the wear on the strap.

I claim:

1. The method of making a check strap for picker sticks of looms which comprises providing a length of tubular woven fabric having one piece cotton warp threads extending lengthwise thereof from one end to the other and a nylon weft thread extending from one end to the other of said length in repeated integrally connected loop formations, each of which extends circumferentially of the tubular fabric and is interwoven with the warp threads, impregnating said length of tubular fabric with a liquid rubber latex compound, cutting said length transversely to provide a section thereof of sufficient length dimension to make the required check strap, folding each edge portion of said section back on the central portion thereof to provide two infolded edge portions of equal width with the infolded edges closely adjacent each other, folding the thus folded section along its median line to bring the folded edges of the folded section into registry with each other and with the edge portions of the original section located within the fold, thereby producing a four-ply endless body having said edge portions located therewithin, and with the nylon weft thread extending lengthwise thereof, stitching the plies together by means of lines of stitching extending lengthwise of the body and then dipping the completed article in a bath of liquid rubber latex, and

then allowing the latex to dry, the portions of the nylon weft thread extending lengthwise of the loop being positioned to take the strain to which the check strap is subjected when in use and serving to provide the check strap with a desired degree of resiliency in the direction of its length.

2. A check strap for picker sticks of looms having a body in the form of a one-piece endless elongated loop of woven fabric presenting a uniform thickness throughout and in which the working strain on the fabric when the check strap is in use is in the lengthwise direction of said elongated loop, said body having resilient characteristics in said lengthwise direction and comprising a plurality of plies of woven tubular fabric integral with each other and each having warp threads extending transversely of the body from one edge thereof to the other, each warp thread extending transversely through all of the plies of the fabric successively, said body also comprising a continuous unbroken weft thread of nylon extending circumferentially of the loop in repeated integrally connected loop portions and having elongated strain-resisting portions thereof extending lengthwise of the loop and in position to take the working strain to which the check strap is subjected when in use and also to provide the check strap with the desired resiliency in the direction of said working strain, and lines of stitching extending circumferentially of said loop, the stitches of each line extending transversely through all the plies and uniting them, the fabric of the plies being impregnated with a liquid rubber latex compound.
